UNITED STATES PATENT OFFICE.

WILLIAM SMITH, OF LONDON, ENGLAND.

ROTARY PUMP.

No. 799,875.

Specification of Letters Patent.

Patented Sept. 19, 1905.

Application filed April 18, 1903. Serial No. 153,337.

To all whom it may concern:

Be it known that I, WILLIAM SMITH, a subject of the King of Great Britain and Ireland, residing at 141 Leytonstone road, Stratford, 5 London, England, have invented a Rotary Pump, of which the following is a specification.

This invention relates to rotary machines applicable as motors, pumps, blowers, ex-10 hausters, and meters, and has for its object to provide an efficient machine of simple and inexpensive construction.

According to the invention the casing of the machine is caused to rotate or to be rotated 15 and is provided with a series of piston-flaps which ride upon an abutment within the casing in such manner that the flaps are maintained in contact with the periphery of the abutment upon the relative rotation of the 20 casing, so that when the machine is used as a pump the water or liquid is carried from one side of the abutment, where it enters, to the other side of the abutment, where it leaves.

The abutment is advantageously made integral with a trunnion coaxial with the rotating casing and may be supported by means of a single or double bracket, the trunnion being provided with a partition forming compartments communicating with the respective 30 sides of the abutment.

Other constructional features of importance are comprised in the invention and are hereinafter more particularly described.

In the accompanying drawings, Figure 1 is 35 a front view of a hand-operated pump provided according to the invention with the casing shown in section. Fig. 2 is a longitudinal central sectional view of the invention with the base shown in elevation. Fig. 3 is 40 a central sectional view of the invention looking downward. Fig. 4 is a front elevation of a constructional modification, showing the casing in section; and Fig. 5 is a central sectional view looking downward on Fig. 4.

45 In carrying the invention into effect in its application to a rotary pump, as illustrated in Figs. 1 to 3 of the accompanying drawings, I provide a rotating casing, which is conveniently formed of two side plates *a* and *b* and 50 an intermediate ring *c*, which latter is tightly pressed between the side plates *a* and *b*, the latter being bolted together by means of bolts *d*, as illustrated. The rotating casing thus constituted is mounted upon a hollow trunnion *e*, which is provided with a central partition *f* and at one extremity is formed as

an abutment *g*. The extremity *e'* of the trunnion is received within a corresponding recess in the side plate *b* of the casing, and lateral ports *h* and *i* are provided on each side 60 of the abutment, communicating, respectively, with the compartments formed in the trunnion by the partition *f*. The abutment *g* is formed as a radial abutment—that is to say, as an abutment reaching from a central position in 65 the casing to the inner periphery of the casing—so as thus to form radial sides within which the respective inlet and outlet ports *h* and *i* may be provided of relatively great length and of as great a width as may be permitted. The formation of the inlet and outlet ports of relatively great length is absolutely essential to the invention, so that, upon the one hand, the blades in passing along the face of the abutment within which the inlet-port is formed may induce a suction by their travel along a considerable extent of the whole radial face of the abutment, so that the space between each of the blades will thus be practically wholly filled and so as to permit 70 of the liquid being accessible to the spaces between the respective blades from the moment their forward extremities emerge from under the extremity of the abutment, while, on the other hand, the relatively long outlet-port is 75 in the same way essential for the proper discharge of the liquid contained between the respective blades in the passage of the blades along the face of the abutment within which the outlet-port *i* is formed, as otherwise part 80 of the liquid carried between the respective blades would be brought down past the outlet and carried around in the casing. The side plate *a* is advantageously provided with a boss *a'* for carrying a bush or gland *j* and 85 packing *k*, by which a tight joint may be screwed between the side plate *a* and the trunnion. The trunnion on its free extremity is provided with a two-way fitting *l*, the one part *l'* serving as the outlet, while the part *l''* 90 serves as the inlet, communicating, respectively, with the outlet and inlet compartments formed in the trunnion by the partition *f*. 95

The ring *c* is reduced at *c'* to permit of the flanges of the respective side plates *a* and *b* 100 passing over and inclosing the lower part of the ring. The lower part of the ring in equidistant positions in circumferential line, which is indicated more particularly in Fig. 1, is provided with a series of almost complete cylindrical holes, each of which leaves a slot on 105 the inner periphery of the ring. These holes 110

- are provided for the reception of the pivot parts n of piston-flaps o . The piston-flaps o are formed of the same size and are made from strips of metal whose upper extremities 5 are formed of a circular shape corresponding to the cylindrical holes provided in the ring c , the said upper extremities fitting in the said cylindrical holes and being maintained in exact position by the side plates.
- 10 It will be understood that the slots on the inner periphery of the ring are of less width than the diameter of the corresponding holes, so that thus when the pivot parts of the piston-flaps are placed into position on the rim 15 they are retained and are in working permitted to assume the positions that are determined by their relation to the abutment g .

The rotating casing may be driven by a belt, or a handle p may be secured to it by means 20 of the plates p' and bolts d' in the manner indicated in Figs. 1 and 2.

It will be understood that on the rotation 25 of the casing in the direction indicated by the arrow, Fig. 1, the piston-flaps o force forward the water from the position within the casing adjacent to the inlet-point h . The piston-flaps o in succession cut off the inlet-port, and the liquid contained between the successive piston-flaps is passed forward to 30 the opposite side of the casing, where it is discharged through the outlet-port i . No necessity arises for the use of springs or mechanisms for maintaining the piston-flaps in their proper position with regard to the 35 abutment.

Instead of the liquid being drawn and being discharged at the same end of the trunnion the trunnion may be provided, as illustrated in Fig. 5, so that the inlet may take place at 40 one side and the discharge at the other, as illustrated in that figure.

In carrying the invention into effect, as 45 illustrated in Fig. 4, I may provide sets of piston-flaps in reverse positions to permit of the employment of the machine or of the pump to work in either direction of the casing. As illustrated in Fig. 4, the piston-flaps o are arranged in reverse positions, and by 50 their use the respective inlet and outlet ports may be reversed.

No limitation is placed to the actual form of the piston-flaps. Instead of the simple form illustrated, the piston-flaps may be formed of any other shape or construction and with 55 edges corresponding in shape to the periphery of the abutment.

In the figures the ring c is provided to allow a clear space equivalent to the thickness of the piston-flaps between the edge of the 60 abutment; but, if preferred, the ring c may be provided with recesses in which the piston-flaps may be caused to lie so that in passing the edge of the abutment the under face of the piston-flap lies flush with the inner periphery 65 of the ring. In either case, however, the

piston-flaps are formed of a shape corresponding to a cylindrical curvature of the casing and the edge of the abutment is advantageously similarly formed.

The invention is not limited to the employment of a rotary casing, as hereinbefore described, as it is obvious that the piston-flaps might be provided upon a rotating frame within a fixed casing. Similarly the invention is not limited to the employment of a central 75 abutment within the casing, as hereinbefore described, as the inlet and outlet ports instead of being provided in the abutment may be provided in the casing.

The invention is of course not limited to the 80 employment of the invention in its application to pumps, as it is obvious that it is equally applicable to the other uses to which an ordinary rotary machine is applicable—that is to say, it is also applicable as a motor, 85 blower, exhauster, and meter.

It is obvious that under certain circumstances the casing may advantageously be fixed with the abutment rotating upon an 90 axle.

In small sizes of machines and in machines which are operated at high speeds springs are advantageously provided in order to maintain the piston-flaps at once in contact with the abutment. These springs are especially necessary also when dealing with thick 95 or viscous liquids.

What I claim as my invention, and desire to 100 secure by Letters Patent, is—

1. In a rotary pump in combination, a rotating casing, piston-flaps freely carried by said casing, a fixed radial abutment within said casing and extending into proximity with the inner periphery of said casing, and radial inlet and radial outlet ports on each side of 105 said abutment, said radial inlet and radial outlet ports being of a length equal to the radius of the cavity in the rotating casing, substantially as described.

2. A rotary pump consisting in combination of a rotating casing, said casing consisting of two side plates and an intermediate ring, said ring carrying partial cylindrical holes near its inner periphery extending completely across said ring, piston-flaps carried 110 by said ring and of a width corresponding to the width of the said ring, said piston-flaps having pivot parts which are let into partial cylindrical holes in the ring aforesaid, and a radial abutment within said casing, radial inlet and radial outlet ports on the respective sides thereof, substantially as described.

3. A rotary pump consisting in combination of a casing, piston-flaps carried by said casing, a radial abutment within said casing, 115 provided with radial inlet and outlet ports on the respective sides thereof, said radial inlet and radial outlet ports being of a length equal to the radius of the cavity in the rotating casing, a trunnion connected to said abutment, 120

a partition dividing said trunnion and abutment into two equal compartments, substantially as described.

4. A rotary pump consisting in combination of a rotating casing, said rotating casing consisting of two side plates and an intermediate ring, said ring being provided with a series of partial cylindrical holes near its periphery, piston-flaps carried by said ring, and having pivot parts let into said partial cylindrical holes in said ring, a fixed radial abutment carrying radial inlet and outlet ports, and a trunnion integral with said fixed radial abutment, said trunnion having a boss lying within a recess on one of the side plates aforesaid, substantially as described.

5. A rotary pump consisting in combina-

tion of a rotating casing, a radial abutment within said casing, and radial inlet and outlet ports on the respective sides of said abutment, said radial inlet and radial outlet ports being of a length equal to the radius of the cavity in the rotating casing, piston-flaps carried by said casing, the edges of said flaps lying upon the said abutment, and said piston-flaps being provided in pairs inclined in reverse directions, substantially as described.

In testimony whereof I have signed my name to this specification in the presence of two subscribing witnesses.

WILLIAM SMITH.
